(57) **CLAIM**

The ornamental design for a combined mobile telephone/MP3 player with charger, as shown and described.

DESCRIPTION

FIG. 1 is a front, side perspective view of a combined mobile telephone/MP3 player with charger showing my new design, the mobile telephone/MP3 player being shown separately for purposes of illustration;

FIG. 2 is a rear, side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a front, side perspective view of FIG. 1 illustrating the combined mobile telephone/MP3 player in an extended position;

FIG. 10 is a rear, side perspective view thereof;

FIG. 11 is a front elevational view thereof;

FIG. 12 is a rear elevational view thereof;

FIG. 13 is a right side elevational view thereof;

FIG. 14 is a left side elevational view thereof;

FIG. 15 is a top plan view thereof;

FIG. 16 is a bottom plan view thereof;

FIG. 17 is a front, side perspective view of FIG. 9 illustrating the combined mobile telephone/MP3 player in an extended position and standing on its stand;

FIG. 18 is a rear, side perspective view thereof;

FIG. 19 is a front elevational view thereof;

FIG. 20 is a rear elevational view thereof;

FIG. 21 is a left side elevational view thereof;

FIG. 22 is a right side elevational view thereof;
FIG. 23 is a top plan view thereof;
FIG. 24 is a bottom plan view thereof;
FIG. 25 is a front, side perspective view of the combined mobile telephone/MP3 player with charger of FIG. 1 shown in position in its charger;
FIG. 26 is a rear, side perspective view thereof;
FIG. 27 is a front elevational view thereof;
FIG. 28 is a rear elevational view thereof;
FIG. 29 is a left side elevational view thereof;
FIG. 30 is a right side elevational view thereof;
FIG. 31 is a top plan view thereof;
FIG. 32 is a bottom plan view thereof;

FIG. 33 is the front, side perspective view of the charger of FIG. 25, the charger being shown separately for purposes of illustration;
FIG. 34 is a rear, side perspective view thereof;
FIG. 35 is a front elevational view thereof;
FIG. 36 is a rear elevational view thereof;
FIG. 37 is a left side elevational view thereof;
FIG. 38 is a right side elevational view thereof;
FIG. 39 is a top plan view thereof; and,
FIG. 40 is a bottom plan view thereof.

The broken lines are for illustrative purpose only and form no part of the claimed design.
